FERROUS BASE CHROMIUM-NICKEL-TITANIUM ALLOY

Gunther Mohling, Loudonville, and Wasil W. Dyrkacz, Newtonville, N. Y., assignors to Allegheny Ludlum Steel Corporation, Brackenridge, Pa., a corporation of Pennsylvania

Application July 19, 1951, Serial No. 237,534

8 Claims. (Cl. 75—128)

1

This invention pertains to ferrous alloys and particularly, to improved austenitic chromium-nickel-titanium ferrous alloys.

Due to recent strides being made in the development of aircraft engines, e. g. jet engines and gas turbines, the need has arisen for new and improved alloys which may be made commercially on a production basis and which will stand up when highly stressed rotating parts are to operate at a temperature of around 1000° to 1350° F. Heretofore, there has been no heat treatable alloy which would fully meet requirements in this respect as to ductility within such a temperature range and which could be produced on a production basis by ordinary arc melting, high tonnage procedure. An alloy of this type for use in rotating parts must not only stand up at such temperatures, but must have other characteristics which will comply with the rather rigid and high requirements of such a utilization.

Heretofore, one type of alloy has been produced which we will hereinafter specify as alloy A that falls within the minimum requirements of such a utilization, except for ductility at the critical (normal embrittlement) temperature of 1000° to 1200° F. to which rotating parts are subjected. Alloy A is thus limited to stationary utilizations as it has an insufficient ductility for rotating parts. Alloy A has the following general composition: small amounts of carbon, silicon, manganese and aluminum, about 30% nickel, 15% chromium and 2.0% titanium. This alloy is a commercial type, but has an extremely short rotating part operating life period, is notch sensitive, and fails suddenly.

Another alloy which will be hereinafter designated as alloy B (see U. S. Patent No. 2,519,406) has been found to generally fulfill the minimum requirements of the subject utilization up to and including operation of the working parts at such temperature, but has only been successfully produced on a pilot plant scale and at a relatively high cost. This latter alloy requires special forging and heat treatment processing and is produced by induction melting. The closely controlled hot-cold forging work ties up forging equipment for long periods of time. We, as well as those skilled in the art, have definitely determined that such an alloy cannot be produced on a large commercial scale by conventional

2

steel making processes and have the requisite properties.

It thus appears that there is a definite and critical need for an improved heat treatable alloy which can be produced in high tonnage and which will have a generally higher ductility at operating temperatures than those now available and which will retain its ductility in the temperature range of 1000°-1200° F. (normal brittle range) and well up to 1350° F. Such temperatures are encountered in ordinary usage of rotating engine parts and thus, the life of such parts is governed by the ductility of the metal. Furthermore, explosion failure which is caused by very brittle characteristics, must be avoided at all costs and if failure is to occur, it must be of a gradual nature, so that steps may be taken to replace the part before its utilization becomes dangerous.

20 It has thus been an object of our invention to provide an improved chromium-nickel-titanium ferrous alloy of an austenitic type which will not only have good forgeability, machinability and an excellent high strength, but will retain its ductility in a moving part utilization and especially, at elevated temperatures of 1000° to 1200° F.

Another object has been to provide a wrought, austenitic, precipitation-hardened alloy which will meet requirements for rotating aircraft engine parts;

30 A further object has been to provide an alloy of this type which can be produced on a commercial production basis and can be simply and inexpensively processed as well as produced;

35 These and many other objects of our invention will appear to those skilled in the art from the further description thereof.

In the drawings, Figures 1 to 3, inclusive, are curves graphically illustrating the improved characteristics of alloys of our invention and Figures 4 to 7, inclusive are photomicrographs showing the effect of various heat treatments on alloys of our invention.

40 In carrying out our invention, we have been able to provide an alloy which has highly superior characteristics under all conditions of utilization, which can be produced by conventional melting practice, whose properties can be developed by heat treatment without special work-

ing and heat treating procedures, and which can be produced relatively inexpensively and processed simply to develop its characteristics. It has a life period far in excess of 1000 hours in rotating engine part utilizations, as based on test data comparisons. It can be hot worked and treated in commercial size heats using standard or conventional equipment. In this alloy, the maximum carbon content is highly critical, and the manganese content provides increased rupture ductility and improved forgeability. Also, vanadium is a highly important and critical element. The alloy permits a higher manganese to silicon ratio. The manganese and vanadium are employed as alloy additions and not as scavengers, as they are introduced directly into the melt and not at the end for cleanup purposes and thus, are essentially in solid solution form in the alloy. The proportioning of vanadium to titanium and molybdenum contents is also highly critical and is believed to constitute the crux of the invention from the standpoint of the specified ranges of chromium, nickel and silicon contents.

In this alloy, although not necessary, cobalt can be added up to 25% to further increase its strength. The element aluminum is generally considered to contribute toward brittleness. We have found that it increases rupture ductility considerably, but at the expense of rupture strength (as evidenced by melt A-416 of Table VI). In our alloy, we have discovered that the adverse effect of a higher aluminum content on rupture strength can be more than offset by the addition of cobalt in amounts up to 25%, e. g. as shown in Table VI, melt A-409 (which contains 1.2% aluminum) is considerably strengthened by the addition of 20% cobalt. The fact that our alloy can take a higher percentage of aluminum is further indicative of its novel characteristics.

Our alloy in its broader aspects contains carbon in relatively low amounts up to .15% maximum, manganese within a range of .50 to 3.00% (not as a scavenger but as an essential alloying element introduced into the solution), silicon up to 1.50%, chromium within a range of about 5 to 22%, nickel within a range of 7 to 50%, titanium within a range of .50 to 3.50%, a relatively low percentage of molybdenum of about .25 to 2.00%, a highly critical percentage of vanadium of .10 to 1.50%, up to 25% cobalt, and up to 2.5% aluminum. In our alloy, the remainder is iron with incidental impurities, such as nitrogen, phosphorus and sulphur.

While in general, increasing the titanium content increases the rupture strength and tensile strength, it also decreases rupture ductility below a useful level when a critical titanium content is reached. In alloy A, this content appears to be about 1.5% titanium, and in alloy B, about 1.9% titanium. In alloys of our invention, useful ductility is maintained up to at least about 3% titanium (see Table IV). This is obtained by proportioning of the other elements and particularly, of the vanadium and molybdenum to offset or reduce the embrittling effect of titanium within the ranges specified. Our alloys, therefore, permit a much higher than ordinary range of titanium, while still insuring high strength combined with good rupture ductility.

The optimum range of our alloy which we have found highly satisfactory consists of carbon in an amount up to .15 maximum, about .5 to 2.0% manganese, about .4 to 1.5% silicon, about 12 to

18% chromium, about 20 to 35% nickel, about 1.0 to 1.5% molybdenum, about .10 to .50% vanadium, and about 1.5 to 2.9% titanium, with aluminum in a maximum amount of 0.35%.

5 A specific alloy which we have produced with optimum results contains about .08 maximum carbon, about 1.0 to 2.0% manganese, about .50 to 1.25% silicon, about 12 to 16% chromium, about 24 to 28% nickel, about 1.0 to 1.5% molybdenum, about .10 to .50% vanadium, about 1.75 to 2.25% titanium, and incidental amounts of aluminum from the addition of ferro-alloys.

15 It will be noted that our alloys save on highly strategic materials and as will hereinafter be shown by test data, are inherently ductile, even at temperatures of about 1200° F., as demonstrated by notched rupture tests. Grain coarsening begins at about 1850° F., see Figures 4 to 7, inclusive. Further, our alloys do not need cold working, since their properties can be developed by a solution treatment and age-hardening (see Figure 5) and they can be handled in melting, forging, and heat treating in the same manner as any commercial alloy.

20 25 Best results are obtained by employing a solution heat treatment of about 1800° F. for one hour and rapidly cooling in a suitable fluid quenching medium (such as oil, air or water), followed by age hardening at about 1325° F. for about 16 hours plus air or furnace cooling (in a gaseous atmosphere). That is, it has been determined that 1800° to 1850° F. is about the highest practical temperature to which the alloy can be raised before grain coarsening sets in and temperatures higher than this, as shown by Table II, produce some gain of strength at the cost of rupture ductility and increased notch sensitivity. Another advantage of our alloys is that a high titanium content can be employed without seriously adversely effecting their ductility, see Table IV. Ductility may be increased by lowering the amount of titanium, but with a greatly reduced rupture strength and tensile strength below about 1.45% titanium. We have found that vanadium is a highly controlling element in offsetting the embrittling tendency of titanium.

25 30 Although with our alloys, better results can be obtained employing any conventional heat treatment, optimum results are obtained by the 1800° F. solution treatment and subsequent age hardening treatment which has been previously discussed.

35 40 As compared to the best alloy available prior to our present invention, namely alloy B (as produced by special procedure), a typical alloy of our invention has a Brinell hardness of 140 to 170 in the solution treated condition, as compared to hardness of 140 to 160 for alloy B, and as solution treated and aged, has an assured hardness of 248 to 341 and higher, as compared to hardness of 248 to 302 for alloy B. It appears that our alloys not only have an increased hardness, strength, etc., but have an increased ductility such that the operating life of working parts can be greatly improved and particularly so, when in operation, they are subjected to heat of up to about 1350° F. and particularly, in the critical range of 1000° to 1200° F. In addition, products made with our alloys can be produced at much lower cost than alloy B, as they do not require special forging and heat treating practice. Center segregation is reduced or eliminated in our alloys when produced in large commercial melts so as to provide material which will have sufficient 45 50 55 60 65 70 75 center ductility in large forgings, such as turbine

rotors. In our alloys, segregation is minimized by limiting the molybdenum content to a 2% maximum.

The V-notch rupture tests as employed herein are an indication of rupture ductility. When high temperature metals of the type herein being con-

an included angle of 60° with a .005 inch radius at the base of the notch.

In the following Table I, we have set forth test data on alloys of our invention on three commercial production heats of 2 and 10 tons made in ingot sizes of 9" to 25" square.

Stress-rupture data on alloy A shows that rupture ductility decreases with an increase in titanium content (see Figure 2). In our alloy, see Table IV and Figure 2, an increase of

ductility. This is true even when hardness is in excess of 290 Brinell which is in contradiction to alloy B. In this connection, attention is called to the data set forth in Table IV and Figure 3.

Solution treated at 1,800° F. and aged at 1,825° F.

titanium content up to 3% may be effected without impairing its rupture ductility, while at the same time increasing room temperature hardness and tensile strength. It will be noted that we can obtain higher yield and tensile strengths (by the use of our permissible higher range of titanium) without adversely affecting rupture ductility due to the controlled vanadium additions. That is, our controlled vanadium additions permit the use of a higher titanium content without seriously increasing notch sensi-

tivity. This is true even when hardness is in excess of 290 Brinell which is in contradiction to alloy B. In this connection, attention is called to the data set forth in Table IV and Figure 3. Although, both the manganese and the vanadium contribute individually to good rupture ductility, they tend to decrease strength. A too high amount of manganese would decrease rupture strength greatly. However, the controlled amount of molybdenum increases the rupture strength. Thus, we add somewhat small amounts of vanadium, keep the manganese at about 1.0 to 2.0% (1.5% optimum) and the molybdenum at about 1.0 to 1.5% (1.25% optimum) to obtain both good rupture strength and ductility. In this connec-

tion, see the data of Table V, wherein melts A-286, A-373 and A-374 represent data on our alloys as compared to alloys having no molybdenum and vanadium or vanadium without molybdenum. It will be noted that melts A-56 and A-57 have a high manganese content and that melt A-54 has a lower content.

										4	13.5	15.2

High aluminum content has a similar effect as manganese in that it increases rupture ductility at the expense of rupture strength, even in the presence of molybdenum. This can be counteracted and the rupture strength greatly increased by the addition of cobalt as shown in Table VI.

In Figure 1, we have graphically shown the effect of the temperature of solution treatment of our alloy, based on standard and V-notch rupture strength and rupture ductility test data taken at 1200° F. and using 60,000 p. s. i.

In Figure 2 of the drawings, we have shown graphically the effect of titanium content on

TABLE VI

Effect of aluminum and cobalt

Melt	C	Mn	Si	Cr	Ni	Ti	Mo	V	Al	Co	Stress-Rupture at 1,200° F.—60,000 p. s. i.			
											Type Test	Hrs. to Rupture	Percent El.	Percent Red. Area
A-416	.04	1.16	.63	14.7	26.0	1.8	1.3	.27	3.1	20.1	Std.	13	30.7	66.6
A-409	.04	1.11	.85	14.8	26.1	1.7	1.2	.32	1.1	—	Std.	491	8.6	15.7
A-409											V-notch	681	—	—

It will be noted that the V-notch test of melt A-409 shows a life of 681 hours which indicates that cobalt added (within the specified range) to our alloy does not make it notch sensitive.

In Figure 3 of the drawings, we have shown graphically a comparison of V-notch rupture life and Standard test rupture life of alloys of our invention with various titanium contents as expressed in Brinell hardness when fully heat treated. The data as to our alloys is taken from Table IV. As compared to the patent disclosure of alloy B, where it is said that notch rupture strength is much lower than regular rupture strength once the hardness goes above about 290 Brinell, this graph shows that the V-notch rupture strength of our alloy is higher than the regular rupture strength all the way up to 341 Brinell. A comparison of the curves of Figures 2 and 3 and Table IV discloses that our alloy has a rupture elongation of about 10% at a hardness of 341 Brinell, as contrasted to .5% of alloy B at the same Brinell.

In our melts, commercial scavengers and de-oxidizers, such as calcium-silicon-manganese, calcium-silicon, silicon-zirconium, Grinal (titanium-aluminum-vanadium), Lan Cer Amp (about 50% lanthanum, 30% cerium and 20% rare earth metals) and L-Metal (about the same composition as Lan Cer Amp), have been used with advantage.

An alloy of our invention is particularly characterized by its ability to develop high strength

¹ Test in progress.

properties (in its heat-treated state) up to 1350° F. with an inherently good rupture ductility and notch rupture strength. That is, the alloying elements of an alloy of our invention are so proportioned as to give it a high rupture ductility and strength at operating temperatures up to 1350° F. and a good ductility within the normally brittle range of 1000° to 1200° F. Such alloy is of an austenitic, ferrous-metal-containing type, such that the remainder is iron or substantially all iron with incidental impurities. For example, production melts may contain impurities such as sulphur, phosphorus, selenium, nitrogen, copper, zirconium, cerium, and lanthanum.

What we claim is:

1. A commercially producible and forgeable austenitic alloy steel suitable for moving part usage and having an inherently good rupture ductility with a high notch rupture strength at elevated temperatures of about 1000 to 1300° F., in which manganese, chromium, nickel, titanium, molybdenum and vanadium are the only essential elements, are critical within the ranges specified, and the specified contents of the elements manganese and vanadium are essentially in solid solution form in the alloy, and in which aluminum may be present in incidental amounts and up to about 2.50% with the presence of cobalt of up to about 25%; the composition consisting of carbon in a relatively small amount up to a maximum of about .15%, about .50 to 3.00% manganese, up to about 1.50% silicon, about 5 to 22% chromium, about 7 to 50% nickel, about .50 to 3.50% titanium, about .25 to 2.00% molybdenum, about .10 to 1.50% vanadium, and the remainder iron with incidental impurities.

2. An improved alloy as defined in claim 1, as further characterized by its fully developed properties when solution treated for about one hour at and quenched from about 1800° F., followed by age hardening for about 16 hours at and quenched from about 1325° F.

3. A commercially producible and forgeable austenitic alloy steel suitable for moving part usage and having an inherently good rupture ductility with a high notch rupture strength at elevated temperatures of about 1000 to 1300° F., in which manganese, chromium, nickel, titanium, molybdenum and vanadium are the only essential elements and the specified contents of the elements manganese and vanadium are essentially in solid solution form and in which aluminum may be present in incidental amounts from the addition of ferro-alloys; and the composition consisting of carbon in a relatively small amount up to a maximum of about .15%, about .50 to 3.00% manganese, up to about 1.50% silicon, about 5 to 22% chromium, about 7 to 50% nickel, about .50 to 3.50% titanium, about .25 to 2.00% molybdenum, about .10 to 1.50% vanadium, and the remainder iron with incidental impurities.

4. A commercially producible and forgeable austenitic alloy steel suitable for moving part usage and having an inherently good rupture ductility with a high notch rupture strength at elevated temperatures of about 1000 to 1300° F., in which manganese, chromium, nickel, titanium, molybdenum and vanadium are the only essential elements and the specified contents of the elements manganese and vanadium are essentially in solid solution form, and in which aluminum may be present up to about .40%; the composition consisting of carbon in a relatively small amount up to a maximum of about .15%, about .50 to 3.00% manganese, up to about 1.50% silicon, about 5 to 22% chromium, about 7 to 50% nickel, about .50 to 3.50% titanium, about .25 to 2.00% molybdenum, about .10 to 1.50% vanadium, and the remainder iron with incidental impurities.

con, about 5 to 22% chromium, about 7 to 50% nickel, about 1.50 to 3.50% titanium, about .50 to 1.50% molybdenum, about .10 to 1.50% vanadium, and the remainder iron with incidental impurities.

5. A commercially producible and forgeable austenitic alloy steel suitable for moving part usage and having an inherently good rupture ductility with a high notch rupture strength at elevated temperatures of about 1000 to 1300° F., in which manganese, chromium, nickel, titanium, molybdenum and vanadium are the only essential elements and the specified contents of the elements manganese and vanadium are essentially in solid solution form, and in which aluminum may be present in a maximum amount of about .40%; the composition consisting of carbon in a relatively small amount up to a maximum of about .15%, about .50 to 2.00% manganese, about .40 to 1.50% silicon, about 12 to 18% chromium, about 20 to 35% nickel, about 1.50 to 2.90% titanium, about 1 to 1.50% molybdenum, about .10 to .50% vanadium, and the remainder iron with incidental impurities.
